UNITED STATES PATENT OFFICE.

EDWARD F. CALDWELL, OF NEW YORK, N. Y., ASSIGNOR TO THE PHENIX
GLASS COMPANY, OF PITTSBURG, PENNSYLVANIA.

DESIGN FOR A GLOBE OR SHADE.

SPECIFICATION forming part of Design No. 26,643, dated February 16, 1897.

Application filed January 13, 1897. Serial No. 619,126. Term of patent 7 years.

To all whom it may concern:

Be it known that I, EDWARD F. CALDWELL, a citizen of the United States, residing at New York, in the county of New York and State of New York, have invented a certain new and useful Design for a Globe or Shade; and I do hereby declare the following to be a full, clear, and exact description of the invention, such as will enable others skilled in the art to which it appertains to make and use the same.

My invention has relation to designs for globes and shades for gas, electric lights, and lamps; and it consists in the shape and configuration hereinafter described, and illustrated in the accompanying drawings, in which—

Figure 1 is a plan view, and Figs. 2 and 3 are side views, of a globe embodying the design.

The body of the globe is in its lower half a frustum of an inverted cone, terminating at the lines *a a* and *b b*. From about the line *a a* the globe is curved upwardly and inwardly to the mouth or upper edge, and from the line *b b* it is curved reversely to form a neck.

The surface of the globe may be appropriately etched above its neck portion and below its upper edge.

What I claim as new is—

The design for a globe or shade, as shown and described.

In testimony whereof I have affixed my signature in presence of two witnesses.

EDWD. F. CALDWELL.
